Attorney

UNITED STATES PATENT OFFICE

JAMES H. MARKS, OF DETROIT, MICHIGAN, ASSIGNOR TO PACKARD MOTOR CAR COMPANY, OF DETROIT, MICHIGAN, A CORPORATION OF MICHIGAN

INTERNAL-COMBUSTION ENGINE

Application filed June 20, 1928. Serial No. 286,833.

This invention relates to internal combustion engines and more particularly to oiling systems therefor.

There is always the possibility of grit damaging the bearings of an internal combustion engine even though the oil may be frequently renewed and to overcome this possibility various designs of oil filtering and refining systems have been used. Substantially all of such systems have the inherent disadvantage that they require personal attention, and where the personal equation enters into such matters the filtering and cleansing devices seldom, if ever, receive the attention requisite to place them in condition so that they may properly perform their intended function. Hence, the present invention proposes to couple a filtering or cleansing device with the drain of the crank case, so that when the crank case is drained periodically the filter or refining device will be automatically cleansed.

An object of the invention is to provide means for cleaning a filter adapted to operate automatically with a means for controlling a drain for the crank case of an internal combustion engine.

Another object of the invention is to provide an oil filter housed within the crank case of an internal combustion engine and connected in the oiling system thereof and to the drain of the crank case so that upon opening the crank case drain the filter is automatically cleansed.

A further object of the invention is to provide a combined filter and a crank case drain for the oiling system of an internal combustion engine, the filter having a cleansing means operating concomitantly with a valve for opening and closing the drain.

A still further object of the invention is to provide a combined oil filter and crank case drain for the oiling system of an internal combustion engine, the filter having a cleansing means arranged to operate automatically with the opening and closing means of the drain, the structure being highly efficient in operation and yet of marked simplicity as a whole and in respect to each of its component parts so that its manufacture is eco-

nomicly facilitated both as regards to parts and their assembly.

Other objects of the invention will appear from the following description taken in connection with the drawings which form a part of this specification, and in which:

Fig. 1 is a vertical sectional view of a crank case illustrating the invention as applied, the crank case being partly broken away;

Fig. 2 is a bottom plan view of the cover, and

Fig. 3 is a top plan view of the housing with the cover removed and the filter element in position.

Referring to the drawings for more specific details of the invention, 10 represents generally the crank case of an internal combustion engine having positioned therein an oil filter 11. As shown, the crank case is of the usual split type having a crank case 12 and an oil pan 13 secured together in the conventional manner. In the bottom of the oil pan adjacent to one side thereof is a suitable drain 14 having arranged therein a valve seat 15 in which is seated a valve 16 having an upwardly extending stem 17 threaded as indicated at 18 and provided with a diametrical slot 19. The valve may be of any preferred type suitable for controlling the passage.

Secured to the side wall of the oil pan immediately above the drain is a housing 20 having formed thereon a boss 21 tapped to receive a drain or clean-out plug 22. As shown, the boss 21 is elongated and externally threaded as indicated at 23, and extends through an aperture 24 in the side wall of the oil pan to receive a nut 25 with suitable washers interposed. This structure provides in addition to a suitable drain or clean-out for the housing, a very desirable support therefor.

In the bottom of the housing 20 is a boss 26 having a bore 27 in axial alignment with the axis of the valve stem 17 and the bore 27 has a threaded portion 28 engaging the threads 18 on the valve stem. Mounted for rotation in the bore 27 is a shaft 29 having formed on the lower end thereof a diametri-

cal tongue 30 engaging the diametrical slot in the top of the valve stem to provide a slip joint for the rise and fall of the valve stem. The shaft 29 carries a cylindrical member 31 provided with a plurality of circumferential slots 32 and a number of passages 33 parallel to the axis thereof. This member constitutes the filtering element.

Suitably secured on the housing is a cover 34 having positioned on the bottom thereof a stud 35 on which is arranged in spaced relation a plurality of plates 36 engaging the slots in the member 31 so that the slots are brushed and cleansed upon rotation of the member 31. The cover is provided with a chamber 37 communicating through an annular opening 38 with the upper end of the passages in the member 31. The chamber 37 has an outlet port 39 adapted to be connected by a pipe line to the manifold of the oiling system and an intake port 40 is provided for admitting oil from a pipe line through which oil is fed under pressure to a chamber 41 in the cover communicating with the housing 20 in which the filtering element is positioned.

The cover has formed thereon a boss 42 bored as indicated at 43 to receive the upper end of the shaft 29 and mounted for rotation in the bore 43 is a shaft 44 provided upon its lower end with a diametrical tongue 45 engaging a diametrical slot 46 in the top of the shaft 29. The upper end of the shaft 44 extends upwardly through the crank case and is provided with a suitable handle 47 by means of which the shafts are rotated to open and close the valve controlling the drain 14 in the bottom of the crank case. It is to be observed that in opening and closing the valve the filter element is rotated and that the finger or plates engaging the slots in the filter element are fixed or stationary, hence the slots are automatically cleansed upon the opening and closing of the valve.

Although this invention has been described in connection with certain specific embodiments, the principles involved are susceptible of numerous other applications that will readily occur to persons skilled in the art. The invention is, therefore, to be limited only as indicated by the scope of the appended claims.

Having thus described the various features of my invention, what I claim as new and desire to secure by Letters Patent is:

1. In combination with an internal combustion engine having an oiling system and a drain therefor, a filter connected in the oiling system and means for cleaning the filter automatically upon opening or closing the drain and without altering the connection of the filter to the oiling system.

2. In combination with an internal combustion engine having an oiling system and a valved drain therefor, a filter connected in

the oiling system, means constantly connected to the drain valve for controlling the drain and means for cleaning the filter automatically upon manipulation of the means for controlling the drain.

3. In combination with an internal combustion engine having an oiling system and a drain therefor, a filter positioned in the crank case of the engine and connected in the oiling system thereof and means for cleaning the filter automatically upon opening or closing the drain without altering the connection of the filter to the oiling system.

4. In combination with an internal combustion engine having an oiling system and a drain therefor, a filter positioned in the crank case of the engine, a valve controlling the drain and means for cleaning the filter automatically upon manipulation of the valve.

5. In combination with an internal combustion engine having an oiling system and a drain therefor, a filter positioned in the crank case of the engine having a clean-out port opening through the wall of the crank case, a valve for the drain and means for cleaning the filter automatically upon manipulation of the valve.

6. In combination with an internal combustion engine having an oiling system and a drain therefor, a filter in the crank case of the engine having a clean-out port opening through the wall thereof, a valve for the drain, a sliding connection between the valve and the filter and means for automatically cleaning the filter upon manipulation of the valve.

7. In combination with an internal combustion engine having an oiling system and a drain therefor, a housing in the crank case of the engine, the housing having a port opening through the wall of the crank case, a filter element in the housing, a valve for the drain connected to the filter element, a cleansing member associated with the filter element, a shaft connected to the filter element extending through the wall of the crank case and means for rotating the shaft to operate the valve and cleanse the filter element concomitantly.

8. In combination with an internal combustion engine having an oiling system and a drain therefor, a housing in the crank case of the engine having a clean-out port opening through the wall thereof, a filter element mounted for rotation in the housing, a cleansing member co-operating with the filter element, a valve for the drain having a sliding connection with the filter element, a shaft for rotating the valve and filter element concomitantly, the shaft extending through the wall of the crank case and a handle for rotating the shaft.

9. In combination with an internal combustion engine having a crank case and a drain therefor, a filter including a housing

and movable filter cleaning means within the housing, and means for operating the cleaning means as the crank case drain is opened or closed.

5 10. In combination with an internal combustion engine having a crank case with a drain opening, a valve for the drain opening a filter including a housing having a drain opening, means movable to clean the filter, 10 and interconnections between the valve and the filter cleaning means arranged to clean the filter as the crank case drain is opened or closed independently of the filter housing drain.

15 In testimony whereof I affix my signature.
